(57) **CLAIM**

The ornamental design for a foot pad for electric vehicle, as shown and described.

DESCRIPTION

FIG. 1 is a top perspective view of a first embodiment of our new design for a foot pad for electric vehicle, showing an illustration of use on an electric vehicle;

FIG. 2 is another top perspective view of the first embodiment thereof, with the exemplary electric vehicle removed for clarity of details;

FIG. 3 is a bottom perspective view of the first embodiment thereof;

FIG. 4 is a front view of the first embodiment thereof;

FIG. 5 is a rear view of the first embodiment thereof;

FIG. 6 is a right side view of the first embodiment thereof;

FIG. 7 is a left side view of the first embodiment thereof;

FIG. 8 is a top view of the first embodiment thereof;

FIG. 9 is a bottom view of the first embodiment thereof;

FIG. 10 is a top perspective view of a second embodiment of a foot pad for electric vehicle, showing an illustration of use on an electric vehicle;

FIG. 11 is another top perspective view of the second embodiment thereof, with the exemplary electric vehicle removed for clarity of details;

FIG. 12 is a bottom perspective view of the second embodiment thereof;

FIG. 13 is a front view of the second embodiment thereof;

FIG. 14 is a rear view of the second embodiment thereof;

FIG. 15 is a right side view of the second embodiment thereof;

FIG. 16 is a left side view of the second embodiment thereof;

FIG. 17 is a top view of the second embodiment thereof;

and,

FIG. 18 is a bottom view of the second embodiment thereof.

The broken lines shown in the drawings are for the purpose of illustrating environmental subject matter and portions of the article that form no part of the claimed design. The shading lines shown in the drawings represent the approxi-
